UNITED STATES PATENT OFFICE.

ALFRED SWENSEN, OF MORTON PARK, ILLINOIS, ASSIGNOR TO THE CABLE COMPANY, OF CHICAGO, ILLINOIS, A CORPORATION OF ILLINOIS.

PRESSURE REGULATOR.

1,405,461.

Specification of Letters Patent. Patented Feb. 7, 1922.

Application filed January 2, 1919. Serial No. 269,244.

To all whom it may concern:

Be it known that I, ALFRED SWENSEN, a citizen of the United States, residing at Morton Park, in the county of Cook and State of Illinois, have invented new and useful Improvements in Pressure Regulators, of which the following is a full, clear, concise, and exact description, reference being had to the accompanying drawing, forming a part of this specification.

My invention relates to pressure-regulators and, more specifically, to pressure-regulators for use with air-motors for advancing the note-sheet of automatic musical instruments.

Difficulty has heretofore been experienced in getting these air-motors to run at the desired speed under changing conditions. One of the factors which have a bearing on the travel of the note-sheet is the suction on the sheet at the tracker. In many pneumatic musical instruments, this suction on the sheet varies with the air-tension in the action wind-chest. The greater the suction on the sheet at the tracker, the greater the power required to draw the sheet over the tracker; hence, the greater the load on the air-motor. Another factor which has a bearing on the speed of travel of the note-sheet is the changing size of the roll of paper on the take-up spool. The note-sheets are often of considerable length, and this results in quite a variation in the diameter of the roll of paper on the take-up spool during the playing of a selection. The diameter of the roll of paper is greater toward the end of the playing of the selection, and the drag of the note-sheet has thus an increased leverage which resists the action of the air-motor. Also, and as a third factor, reduction in size of the music-roll as it is unwound in many cases, causes effective increase in the drag of the usual music roll friction-brake. It is often the case that the higher air-tensions are used toward the end of a selection, so that the three factors referred to are often cumulative in their effect toward the end of a selection; that is, the size of the roll of paper on the take-up spool is greater, the size of the music-roll has been reduced and the drag due to the increased suction on the tracker is greater. In some instances, this increased drag and the change in leverage are sufficient to stall the motor. These causes of difficulty are more or less structural in

character, and I have described them at length because I believe they are already recognized as being the most difficult to correct or counteract. Besides these, however, there are the well-recognized troubles due to tarnished or soiled trackers, gummed bearings and friction-brakes, and probably other disarrangements more or less easy to correct, all of which, nevertheless, assist in producing and in affecting the working load of the motor.

One of the objects of my invention is to provide improved means for compensating for the increased load on the motor by controlling the power supplied to the motor. Further objects will appear from the detailed description to follow and from the appended claims.

In the drawings, in which one embodiment of my invention is shown—

Fig. 1 is a front view of a player-piano embodying my invention, parts being broken away to show the interior construction;

Fig. 2 is a horizontal section, on the line 2—2 of Fig. 1;

Fig. 3 is a vertical section, on the line 3—3 of Fig. 2;

Fig. 4 is a section, on the line 4—4 of Fig. 2;

Fig. 5 is a fragmentary view, showing part of the regulator construction;

Fig. 6 is a section, on the line 6—6 of Fig. 5; and

Fig. 7 is a section, on the line 7—7 of Fig. 5.

In order to give a general idea of my invention, it is here stated that, in the embodiment disclosed, it is shown in connection with a player-piano having any usual or suitable roll-box, air-motor, and air-pump. An air-pressure-regulator is interposed, in the communication between the pump and the air-motor, to prevent changes in the pumping having an undue effect on the operation of the motor.

In order to compensate for the three varying factors hereinbefore mentioned, viz, the variable drag on the note-sheet due to variations in suction at the tracker and to variations in the size of the music-roll, and the varying size of the roll on the take-up spool, as well as for other varying factors which act to increase the load on the motor, I provide a bellows which resists the action of the pressure-regulator and is controlled

75

110

by air which is regulated by said pressure-regulator.

Referring now to the drawings in detail, the player-piano shown comprises the roll-box 10; the air-motor 11; the air-pump 12; the pressure-regulator 13; and the compensating device 14.

The flow of air from the motor 11 to the pump 12 is through the conduit 15, tempo-
10 valve-box 16, wind-way 17, regulator 13, and wind-chest 18. The tempo-valve-box 16 is provided with any usual or suitable tempo-valve 19, which may be manually operated by means of the tempo-lever 20 to control
15 the passage of air through the port 21. In order to cut out the regulator during re-winding of the note-sheet, a regulator bypass valve 21^a is provided, which controls a port 21^b. This valve 21^a is opened, when the
20 tempo-valve 19 is moved to the extreme right, by the engagement of the tempo-valve 19 with a projection 21^c secured to the valve 21^a, the extreme right-hand position of the tempo-valve corresponding to rewind position.
25 When this valve 21^a is thus opened, the regulator 13 is rendered ineffective and the air-motor 11 is in direct communication with the wind-chest 18 through the port 21^b. This direct communication between the air-motor and wind-chest causes the air-motor to rewind the note-sheet quickly.

The regulator 13 comprises a regulator-bellows 22, a regulator-valve 23, and a valve-lever 24, to one end of which the valve 23 is secured and the other end of which engages the movable leaf of the bellows 22. This valve-lever and associated parts will be described more in detail hereinafter. A U-shaped spring 25^a, having its lower end secured to the fixed leaf of the bellows 22 and its upper end secured to the movable leaf of the bellows 22, exerts a bellows-opening effect on said bellows.

Air enters the bellows 22 from the wind-way 17 through the port 25 and leaves through the port 26. The port 26 is controlled by the valve 23.

The compensating device 14 comprises a hinged bellows 27, the interior of which is in communication with regulated air in the tempo-valve-box 16 through the flexible tube 28. The connection of the tube 28 with the bellows 27 is through a nipple 29, inserted in a slanting hole 30 in the fixed leaf 31 of the bellows 27. A leaf-spring 32 has one end thereof firmly secured to the upper movable leaf 33 of the bellows 27, the other end engaging the head of a screw 34 which is threaded into an arm 35 secured to the movable leaf of the regulator-bellows 22. An arm 36 is secured, to the movable leaf 33 of the bellows 27, in position to be engaged by the movable end of the leaf-spring 32 to limit the movement of the leaf-spring with
60 respect to the movable leaf 33 of the bel-

lows. The intermediate leaf 37 of the bellows 27 is provided with an opening 38, in order that there may be free communication between the upper and lower chambers of the bellows.

Going back to the description of the regulator-valve-mechanism, and referring particularly to Figs. 5, 6, and 7, the lever 24 is pivotally or tiltably mounted on a fulcrum-block 39 which has a knife-edge 40 about which the lever tilts as an axis. The axis about which the lever 24 tilts is thus located to one side of the lever. In order to hold the lever 24 in proper position with respect to the fulcrum-block 39, a plate 40^a is secured to the lower face of the lever 24 by means of screws 41, and this plate 40^a is, in turn, secured to the fulcrum-block 39 by means of screws 42, extending through openings 43 in the plate 40^a and threaded into the fulcrum-block 39. The diameter of the openings 43 is slightly greater than the diameter of the shank of the screws 42 and the screws have the lower surfaces of their heads slightly above the plate 40^a so that the engagement between the screws 42 and the plate 40^a is such as not to interfere with the tilting movement of the lever 24, but is such as to hold the lever 24 in proper position with respect to the fulcrum-block 39 and to prevent the lever 24 from skewing or twisting sideways. The plate 40^a is also provided with two holes 44 to permit access to the heads of the screws 45 which secure the fulcrum-block 39 in place.

The valve 23 is secured to the lever 24 by means of a screw 46, extending through an opening 47 in the valve 23 and threaded into the lever 24. A washer 48 of soft leather is interposed between the head of the screw 46 and the valve 23. The diameter of the opening 47 is greater than the diameter of the shank of the screw 46, so that the valve 23 is free to tilt slightly with respect to the screw 46 to enable the valve 23 to assume the proper position with respect to the port 26.

In order to make the operation clearer, a description of what would be the operation under varying conditions, without the compensating device 14 will first be given, and then a description of the operation and effect of operation with the compensating device 14 will be given.

Considering, first, the operation with the compensating device 14 omitted, I will describe this operation with the assumption that there are no changes occurring in the air-tension but that there are changes occurring in the motor load due to various causes, such as variations in the size of the roll of paper on the take-up spool, variations in the braking effect on the music-spool as the size of the roll of paper on the music-spool changes, differences in friction with note-

sheets of different material, and changes in friction between the note-sheet and the tracker caused by variations in the number of notes being simultaneously sounded. All 5 of these changes in motor load may take place without any change in the air-tension. Assuming, then, that the compensating device 14 is omitted and that there is no appreciable change of air-tension in the 10 wind-chest 18, the operation of the parts described is as follows: When the air-pump 12 is operated, air is drawn through the motor 11, conduit 15, valve-box 16, wind-way 17, and regulator 13, into the wind-chest 18. 15 The movable leaf of the regulator-bellows 22 assumes a position in which the bellows-closing effect, due to the difference in pressure inside and outside the bellows, is just counterbalanced by the bellows-opening effect 20 of the spring 25^a. The position which the movable leaf assumes is dependent, not only on the bellows-opening effect of the spring 25^a, but also upon the throttling effect of the regulator-valve 23 with respect 25 to the port 26. As the bellows 22 collapses, its movable leaf bears against the lever 24 and moves the valve 23 to further restrict the flow of air through the port 26. This tends to prevent further decrease in the 30 tension of the air in the bellows 22 and to lessen the bellows-closing effect caused by the difference in pressure inside and outside of the bellows. When this bellows-closing effect, due to the tension or difference 35 in pressure, is equal to the bellows-opening effect of the spring 25^a, the bellows 22 will be in a state of equilibrium. If now, without appreciable change in air-tension in the wind-chest 18, the load on the motor 11 40 is increased, (as by a change in size of the rolls on the take-up spool and music-spool, a change in the number of notes being simultaneously sounded, or by the material of the particular note-sheet causing an increase 45 in the friction between the note-sheet and the tracker,) the first effect of this increased load on the motor will be a slowing up of the motor and a reduction in the amount of air flowing into the motor. This 50 reduction in the amount of air flowing into the motor causes a reduction in the absolute pressure in the motor, conduit 15, valve-box 16, wind-way 17, and bellows 22. This reduction of absolute pressure in the bellows 55 22 results in an increase in the bellows-closing effect and an increase in the difference in pressure inside and outside of the bellows, which causes the bellows, 22 to begin to collapse. This collapsing movement of the 60 bellows 22 causes the valve 23 to still further restrict the port 26, and the collapsing movement continues until the bellows-closing effect, due to the tension in the bellows, is 65 equaled by the bellows-opening effect of the spring 25^a, the bellows-opening effect of

the spring 25^a increasing as the bellows collapses.

If change in motor load alone were to be considered (that is, if there were no question of change of air-tension in the wind-chest 18 to be considered), the spring 25^a might be so designed that its bellows-opening effect would increase very quickly with the collapse of the bellows, so that the air-tension in the motor 11 would increase very 75 quickly without much restriction of the port 26. This, however, would impair the action of the regulator 13 as a regulator for preventing changes of air-tension in the wind-chest 18 from causing material variations of 80 air-tension in the air-motor, as will be pointed out more in detail hereinafter.

I will now describe the operation and effect (still considering the compensating device 14 omitted) when not only the load on the motor is changed, but also the air-tension in the wind-chest 18 is changed, as, for instance, for the purpose of changing the power of playing. Assuming, therefore, that the air-tension in the wind-chest 18 is 85 increased, the air-tension in the bellows 22 will also be increased. The extent to which the tension in the bellows 22 will be thus increased is, however, limited by the action of the valve 23, since, as the tension in the 90 bellows 22 increases and the movable leaf of the bellows 22 moves to a new position, the valve 23 will be moved to still further throttle the port 26 and limit the increase of air-tension in the bellows 22. The bellows 22 100 will, however, collapse until the bellows-closing effect, due to the air-tension in the bellows, is again equaled by the bellows-opening effect of the spring 25^a, the bellows-opening effect of the spring 25^a increasing as 105 the bellows collapses. The spring 25^a might be so designed that its bellows-opening effect would not increase quickly as the bellows collapses, so that a slight change in tension in the bellows 22 would cause a considerable restriction of the port 26 and thus prevent variations of tension in the wind-chest 18 from materially changing the air-tension of the bellows 22.

As indicated above, however, such a design of the spring 25^a would not be one which would maintain tempo under a change of load on the motor due to a change of air-tension. In other words, the regulator-spring 25^a, to take care of changes in 115 motor load, not due to changes in pumping, should be made so that its bellows-resisting action would increase quickly with the collapse of the bellows, and, on the other hand, in order to prevent material change of air-tension in the bellows with changes of tension in the wind-chest 18, the regulator-spring 25^a should be so designed that its bellows-resisting action would not increase 125 quickly with the collapse of the bellows, 130

The two principles are opposed and the spring could not be designed to take care of both.

The variations of air-tension in the wind-chest 18 also cause variations in the load on the motor. This is because the suction on the note-sheet at the tracker increases and decreases with the tension in the wind-chest 18. By proportioning the regulator-valve 5 area and other regulator parts, the regulator could be made to maintain tempo, notwithstanding variations in motor load which were due to variations in pumping, but variations of load not due to changes in pumping 10 (such as those due to changes in the size of the rolls on the take-up spool and music-spool, variations in the number of notes being simultaneously sounded, and variations in friction due to note-sheets of 15 different material) would cause changes in tempo.

It is to provide a construction which will enable tempo to be maintained, notwithstanding variations of air-tension in the wind-chest 18 and notwithstanding variations in the motor load, which latter may be due to variations of air-tension in the wind-chest 18 and to other causes previously mentioned as well, (such as a change in size of 20 the rolls on the spools, etc.,) that my compensating device is designed.

I will now describe the operation and effect when my compensating device is provided. If, for any cause, whether due to 25 an increase of tension in the wind-chest 18 resulting in an increase in suction on the note-sheet at the tracker, or due to causes not depending on the air-tension in the wind-chest, (such as the variation in size 30 of the rolls on the spools, etc.,) the load on the motor is increased, the immediate effect is to slow up the motor and lessen the amount of air flowing into the motor. This results in an increase in air-tension in the 35 bellows 22, and it also results in an increase in air-tension in the bellows 27. The increase in air-tension in the bellows 22 tends to close that bellows against the action of the spring 25^a, but the increase in tension 40 in the bellows 27 tends to open the bellows 22 through the action of the leaf-spring 32. The greater the air-tension in the bellows 27, the greater will be the pressure exerted 45 by the spring 32 with a bellows-opening 50 effect on the bellows 22. The position assumed by the bellows 22 will be one in which the bellows-closing effect, due to the air-tension in the bellows 22, will be balanced by the bellows-opening effect of the spring 25^a plus 55 the bellows-opening effect of the spring 32.

As stated above, a regulator 13 may be 60 designed which will prevent variation of tension in the wind-chest 18 from materially changing the air-tension in the bellows 22, 65 and such a regulator may be used with the

compensating device 14. With this combination, a change of pressure in the wind-chest 18 will have very little effect on the compensating device 14. The compensating device 14 does, however, respond to a change 70 of pressure in the tempo-valve-box 16, due to a slowing down of the motor, because the bellows 27 of the compensating device 14 is directly connected with the tempo-valve-box 16 through the tube 28. 75

From the construction and operation of the compensating device 14, it follows that its tendency, when the motor load is increased, is to open the bellows 22. This action of the compensating device upon the 80 regulator-bellows 22, being transmitted through the leaf-spring 32, may be considered as a load-controlled booster which acts to assist the spring 25^a, the degree of such assistance depending upon the strain 85 placed upon spring 32 by the air-tension within bellows 27. Thus, the tendency of the compensating device, on an increased motor load, is to increase the power supplied to the motor, to enable the motor to maintain the desired tempo with the increased 90 load.

I claim as new and desire to secure by Letters Patent of the United States:

1. The combination with an air-motor and 95 an air-pressure-regulator for said air-motor, of means for controlling said air-motor, and means whereby the first said means may be controlled by the load on said air-motor and by the air regulated by said regulator. 100

2. The combination with note-sheet-ad- 105 vancing mechanism including an air-motor, and a regulator for regulating the pressure of the air which actuates said air-motor, of means for controlling said note-sheet-ad- 110 vancing mechanism, and means whereby the first said means may be controlled by the pressure of the air regulated by said regulator.

3. The combination with note-sheet-ad- 115 vancing mechanism including an air-motor, and a regulator for regulating the pressure of the air which actuates said air-motor, of means for controlling said air-motor, and means whereby the first said means may be 120 controlled by the pressure of the air regulated by said regulator.

4. The combination with note-sheet-ad- 125 vancing mechanism including an air-motor, and an air-pressure-regulator for regulat- 130 ing the pressure of the air which actuates said air-motor, of means for controlling the action of said air-pressure-regulator, and means whereby the first said means may be controlled by the pressure of the air re- 135 gulated by said regulator.

5. The combination with note-sheet-ad- 140 vancing mechanism including an air-motor, a wind-chest of variable air-pressure, and a regulator for regulating the pressure of the 145

- air which actuates said air-motor, said regulator comprising a bellows in communication with said air-motor and also in communication with said wind-chest; a valve 5 for controlling said communication with said wind-chest, and means whereby a collapsing movement of said bellows will cause said valve to throttle said communication with said wind-chest, of a second bellows 10 acting to resist the collapsing movement of said regulator bellows, and means whereby said second bellows is controlled by the pressure of the air regulated by said regulator. 15 6. The combination with note-sheet-advancing mechanism including an air-motor, a wind-chest of variable air-pressure, said air-motor being in communication with said wind-chest, and a regulator for controlling the pressure of the air which actuates said air-motor, comprising a bellows in communication with said air-motor and also in communication with said wind-chest, of a second bellows 20 acting on said regulator bellows, and means whereby said second bellows is controlled by the pressure of the air regulated by said regulator. 25 7. The combination with note-sheet-advancing mechanism comprising an air-motor, a wind-chest of variable air-pressure, said air-motor being in communication with said wind-chest, and a regulator for regulating the pressure of the air which actuates said air-motor, comprising a bellows in communication with said air-motor and also in communication with said wind-chest, of a second bellows, means whereby said second bellows is controlled by the pressure of the air regulated by said regulator, and yielding means 30 actuated by said second bellows for acting on said regulator bellows. 35 8. The combination with note-sheet-advancing mechanism comprising an air-motor, a wind-chest of variable air-pressure, said air-motor being in communication with said wind-chest, and a regulator for regulating the pressure of the air which actuates said air-motor, comprising a bellows in communication with said air-motor and also in communication with said wind-chest, of a second bellows, means whereby said second bellows is controlled by the pressure of the air regulated by said regulator, and yielding means 40 actuated by said second bellows for acting on said regulator bellows, comprising a spring secured to the movable part of said second bellows. 45 9. The combination with note-sheet-advancing mechanism comprising an air-motor, a wind-chest of variable air-pressure, said air-motor being in communication with said wind-chest, and a regulator for regulating the pressure of the air which actuates said air-motor, comprising a bellows in communication with said air-motor and also in 50 communication with said wind-chest, of a second bellows, means whereby said second bellows is controlled by the pressure of the air regulated by said regulator, yielding means actuated by said second bellows for 70 acting on said regulator bellows, and a stop for limiting the movement of said yielding means. 75 10. The combination with a motor, a conduit connected with said motor, and a fluid-controller in said conduit for controlling said motor, of means controlled by the fluid in said conduit between said fluid-controller and said motor for controlling said motor. 80 11. The combination with a motor, a conduit connected with said motor, and a fluid-regulator in said conduit for said motor, of means controlled by the fluid in said conduit between said fluid-regulator and said motor for controlling said motor. 85 12. The combination with a motor, a conduit connected with said motor, and a fluid-regulator in said conduit for said motor, said fluid-regulator comprising means for controlling the fluid and means controlled 90 by the fluid in said conduit, of means controlled by the fluid in said conduit between said fluid-regulator and said motor for controlling said fluid-regulator. 95 13. The combination with a motor, a fluid-regulator for said motor, a conduit connecting said motor with said fluid-regulator, and a fluid-controller in said conduit, of means controlled by the fluid in said conduit between said fluid-controller and said motor 100 for controlling said fluid-regulator. 14. The combination with an air-motor, a conduit connected with said air-motor, and a tempo-valve in said conduit for controlling said air-motor, of means controlled by the pressure in said conduit between said tempo-valve and said air-motor for controlling said air-motor. 105 15. The combination with an air-motor, a conduit connected with said air-motor, and an air-pressure regulator in said conduit for said air-motor, of means controlled by the pressure in said conduit between said regulator and said air-motor for controlling said air-motor. 110 16. The combination with an air-motor, a conduit connected with said air-motor, and an air-pressure regulator in said conduit for said air-motor, said regulator comprising a valve in said conduit and a valve-controlling 115 member controlled by the pressure in said conduit, of means controlled by the pressure in said conduit between said regulator and said air-motor for controlling said regulator. 120 17. The combination with an air-motor, an air-pressure regulator for said air-motor, a conduit connecting said air-motor with said regulator, and a tempo-valve in said conduit for controlling the communication 130

between said air-motor and said regulator, of means controlled by the pressure in said conduit between said tempo-valve and said air-motor for controlling said regulator.

5. 18. The combination with an air-motor, a conduit connected with said air-motor, and an air-pressure regulator in said conduit for said air-motor, of means for controlling said air-motor comprising a chamber having a 20
10 movable wall, the position of which varies according to variations in the pressure in said conduit between said regulator and said air-motor.

19. The combination with an air-motor, a 25
15 conduit connected with said air-motor, and a

tempo-valve in said conduit for said air-motor, of means for controlling said air-motor comprising a chamber having a movable wall, said chamber being directly connected with the portion of said conduit between said tempo-valve and said air-motor, whereby the position of the movable wall thereof varies according to variations in the pressure in said portion of said conduit.

In witness whereof, I have hereunto subscribed my name.

ALFRED SWENSEN.
